TELESCOPING FLUE

Marc Resek, Cleveland Heights, Ohio, assignor to
Perfection Stove Company, Cleveland, Ohio, a
corporation of Ohio

Application July 14, 1943, Serial No. 494,743

12 Claims. (Cl. 126—280)

1

My present invention is a telescoping flue for use with combustion apparatus, and it was developed in conjunction with the liquid fuel heating apparatus that forms the subject matter of my copending application Serial No. 479,038. The apparatus of said application is intended primarily as a heater for internal combustion engines of automotive vehicles, such as motorized military equipment, including trucks, tanks and the like.

Where the heater is installed in the engine compartment of a truck or like vehicle beneath the hood, it is desirable, for obvious reasons, when the heater is placed in condition for use, to have the flue by which the products of combustion are carried off extended to a considerable height above the plane of the hood, incidentally through an opening in the hood; and, when the heater is not in use, to have the flue contracted beneath the hood and, preferably, said opening closed by a shutter or other suitable means. The nature and purpose of the heater requires its use only when the vehicle is standing, wherefore, when the vehicle is in operation, the flue is contracted and entirely out of the way.

The more general objects of the invention are to provide a telescoping flue that is substantial and relatively simple in construction, and that can be easily and quickly extended and contracted; also, to provide a flue comprising telescoping sections that are connected together, when the flue is extended, by firm, interlocking and leak-proof joints and the sections of which, when the flue is in any other than fully extended condition, loosely interfit so that each retractable section may readily slide within the one next larger in diameter and with sufficient clearance to avoid the scraping off of an appreciable amount of soot that has been deposited on the interior of the larger section.

Another object of the invention is to provide a telescoping flue having a soot collecting basin or trap at its lower end into which any soot that is scraped off during the contraction of the flue will collect and from which it may readily be discharged; and a further object is to provide a closure for said basin or trap that automatically closes when the flue is extended and which likewise opens each time the flue is contracted thereby to discharge the contents of the basin or trap.

The foregoing objects, with others that will be apparent from the following detailed description of the invention, are attained in the construction illustrated in the accompanying drawings where-
in Fig. 1 is a side elevation of my improved tele-

2

scoping flue in contracted condition and connected to a vehicle engine heater, a part of the engine and adjacent portions of the vehicle structure being shown in dot-and-dash lines; Fig. 2 is a similar view with the engine and all but a fragment of the vehicle hood omitted and with the flue in extended condition; Fig. 3 is a perspective view of the flue cap and the adjacent portion of the upper flue section to which the cap is attached; Fig. 4 is a central vertical section through the flue, substantially on the line 4—4 of Fig. 1, showing the flue contracted and with the upper left hand corner in elevation, this and the following figure being on the same scale and one 15 considerably enlarged over that of Figs. 1 and 2; Fig. 5 is a central vertical section through the flue, in a plane at right angles to that of Fig. 4, showing the flue extended, parts of the flue in this and in the preceding view being broken out 20 in order to shorten the views, and Fig. 6 is a transverse section through the joint between the top and middle sections on a further enlarged scale, the plane of section being indicated by the line 6—6 of Fig. 5.

25 The flue, as herein illustrated, comprises three tubes or sections, although it may consist of two, or of any greater number that is practical. The bottom or base section is designated 1, the middle or intermediate section 2, and the top section 3.

30 The bottom section has a side opening 5 (Fig. 5) near its lower end over which is disposed a shell 6 whose edge portion is suitably connected, as by welding, to the section 1 about said opening. The shell has a bottom wall 7 provided with an opening 8 that is surrounded by a depending collar 9

35 through which the flue has communicative connection with the combustion chamber of the heater 10. Details of this heater are disclosed in my application aforesaid.

40 The bottom portion of the flue, below said opening 5 of section 1, constitutes a soot collecting basin or trap, and the same is provided with a bottom closure 15 shown in section in Fig. 4 and in elevation in Fig. 5, the closure desirably

45 being formed from sheet metal with a peripheral flange 16 that is adapted to seat against the bottom of the section 1. A cylindrical portion 17 rises from the inner edge of the flange 16 and merges into a frusto conical part 18 having a closed top. The closure is guided within the tube by the vertical branches 19 of members 20, desirably formed from strap metal and welded or otherwise fastened to the closure, and at their tops said members are provided with seats 21

50 against which the lower ends of the intermedi-
55

ate and top flue sections 2 and 3 bear when the flue is in contracted condition, as will herein-after more fully appear. When the flue is ex-tended, as shown in Figs. 1 and 5, and the weight of the flue sections 2 and 3 is thus removed from the seats 21, the closure 15 is lifted by a spring 23 and is held by said spring with its flange 16 against the bottom of the section 1. This spring bears at its upper end against the circular top wall of the closure 15 and at its lower end surrounds a positioning boss 24 of a spring seat 25 that consists of an annulus that is desirably slightly less in diameter than the internal diameter of the lower end of the closure 15. The lower convolutions of the spring 23 and the 15 spring seat 25 are shown in section in Fig. 4, while in Fig. 5 the same parts are shown in elevation. The seat 25 is carried by the central portion of a U-shaped bail 26 whose ends are connected by pivot members 27 to the opposite 20 sides of the flue section 1. The bail 26 is adapted to be held in a position with the spring seat 25 in vertical alignment with the flue by a set screw 28 that is threaded through one of the side 25 branches of the bail and is arranged to engage the side of the flue section 1. By loosening the screw 28, the bail is free to be swung to a position to one side of the flue, as shown in dotted lines in Fig. 5.

Fitted within the top of the flue section 1, and fastened thereto, as by welding, is a locking ring 30 that is surrounded at its upper end by an inwardly directed flange 31, the underneath surface of which constitutes a seat 1^a. The peripheral wall of said ring is provided with a number, desirably three, of L-shaped slots 32 having relatively wide mouths, as indicated in Fig. 5; and the bottom edge 33 of the lateral branch of each slot is inclined upwardly at a slight angle to the horizontal in a direction away from the entrance end of the slot. Also, the wall 34 at the entrance end, opposite the lateral branch, is inclined upwardly and at a substantial angle toward said branch, for a purpose hereinafter appearing. The intermediate flue section 2 has a circumferential portion 35 adjacent its lower end that is enlarged to fit within the locking ring 30, a shoulder being thus provided between the body portion of the tube and said circumferential portion that constitutes a seat 2^a for engagement with the previously mentioned seat 1^a. Projections 37 on the portion 35 of section 2 are arranged to enter the slots 32 as said section is extended and, if necessary, turned to register the projections with the slots. As the projections enter the slots they engage the walls 34 and are deflected into the lateral branches, this action initiating the turning of section 2 in the proper direction to shift the projections 37 into said lateral branches and cause the projections to ride up the inclined edges 33, thereby to urge the aforesaid seats 1^a and 2^a into firm contact with each other.

The projections 37 desirably consist of the heads of rivets, one of which is shown in section in Fig. 6, the shanks of the rivets being extended through apertures in the portion 35 of section 2 and upset on the inner side thereof.

A joint substantially like that above described occurs between the upper end of section 2 and the lower end of section 3. The locking ring of the present joint is designated 40, one of the L-shaped slots of which is shown at 41 in Fig. 5, and the enlarged circumferential portion 42 of the flue section 3 is equipped with projections, the one shown in Fig. 5 being designated 43. The

present joint includes seats that are formed by the underneath side of the top flange 44 of the locking ring 40 and the shoulder between the body portion of section 3 and the enlarged portion 42 thereof. In the present case, the flange 44 of the locking ring is flush with the top of the flue section 2, instead of being at a higher elevation like the flange 31 of the locking ring 30 of the first described joint.

10 A cap 50 is fastened to the upper end of the top flue section 3, as by having a collar 51 thereof inserted into the upper end of said section and parts of said section (one of which is designated 52 in Fig. 4) depressed inwardly into apertures 53 of said collar. The body portion of the cap 50 is frusto conical in shape and is joined with the collar 51 at its inner edge and at its outer edge is surrounded by a horizontal flange 55. The flange is cut away or sheared off at one side along a straight line, as shown at 56, and adjacent one end of its straight side the flange is deformed to provide a detent 57 and a stop 58, between which is a shallow socket 59. Lugs 60 are incorporated in the cap and are shown as rising from diametrically opposite portions of the flange 55 to facilitate turning the cap for a purpose hereinafter appearing.

Arranged to cooperate with the flange 55, when the flue is contracted, is the inturned end of a hook 62 whose base portion 63 is welded or otherwise fastened to the flue section 1.

The flue is desirably anchored in the region of the upper end of its base section 1 to a part of the vehicle structure as, for example, the engine. In the present case a band 65, that encircles the flue section 1, is fastened to a bracket 66 that is secured to and rises from the engine E. The hood H of the vehicle has an opening h in vertical alignment with the flue, and said opening is adapted to be closed by a shutter h' when the flue is contracted. The parts are illustrated in this condition in Fig. 1. The shutter is shown as connected by a pivot member h² to the hood, and is provided with a finger piece h³ that projects through the opening h. By means of the finger piece h³ the shutter may be swung to one side to uncover the opening h, so that the flue may be extended through said opening, as illustrated in Fig. 2.

When it is desired to contract the flue, the section 2 is turned in a direction (counterclockwise according to the present construction) to remove projections 37 from the lateral branches of the L-shaped slots 32 of the locking ring 30, when the section 2 may be lowered into the base section 1, the initial downward movement of section 2 withdrawing its enlarged circumferential portion 35 from the locking ring. After this initial movement, the section 2 descends freely into section 1 until its lower end engages the seats 21 of the members 20 that are incorporated in the closure 15. In the meantime, the projections 43 of the top section 3 are disengaged from the lateral branches of the slots 41 of the locking ring 40 so that the top section may be lowered into the intermediate or middle section 2, the top section, in turn, taking its place upon the seats 21 of the aforesaid members 20. The retractable sections are then further depressed so as to lower the closure 15 in opposition to the spring 23, the top flue section being orientated to a position wherein the cut away part 56 of the flange 55 will pass the end of the hook 62. With the flange 55 below the plane of said end of the hook, the top section is turned in the direction designated

by the legend on the flange 55, clearly shown in Fig. 3, so as to cause the hook to override the detent 57 and assume a position in line with the socket 59, the parts being arrested in this relation by engagement of the stop 58 with the in-turned end of the hook. When downward pressure on the cap 50 is relaxed, the spring 23 will lift the retractable flue sections and hold the cap against the hook.

In the retraction of the flue sections 2 and 3, 10 soot will likely be loosened from the inner surfaces of the different sections and fall into the soot collecting basin or trap at the bottom of the flue. Now, as the retractable sections are fully depressed, the closure 15 will be opened and most 15 of the soot will drop by gravity through the opening between the lower ends of the flue sections and the closure 15. Thus, each time the flue is contracted, the basin or trap will be automatically emptied.

When it is desired, for any reason, to remove the closure 15, the lower end of the spring 23 is disengaged from the boss 24 of spring seat 25 and the spring is withdrawn from its position between said seat and the top of the closure 15. Now, upon loosening the set screw 28, the bail may be swung to one side, as illustrated in dotted lines in Fig. 5, and the closure 15 dropped. This arrangement also facilitates assembly of the telescoping sections of the flue because, with the bail and spring seat swung to one side, the flue sections 2 and 3 may be inserted through the bottom of the base section 1 and, with this done, the cap 50 may be attached in the manner already described to the top end of section 3.

Having thus described my invention, what I claim is:

1. A telescoping flue for combustion apparatus having adjacent its lower end means for communicatively connecting it to such an apparatus and being open at the top and unobstructed between its open top and the aforesaid means, said flue comprising at least two sections, one of which fits within the other with appreciable clearance when the sections are in any but fully extended condition, the outer section having a circumferential portion adjacent one end of reduced internal diameter, and the inner section having a circumferential portion adjacent its opposite end of increased external diameter and of a size to fit rather closely said portion of the outer section, the outer and inner sections being surrounded in the vicinity of said portions, respectively, by inwardly and outwardly extending seats, and inter-engaging means on the two sections that cooperate when the flue is extended and said sections are relatively rotated for urging said seats into firm contact with each other, said means consisting of radial projections on one section and parts on the other section having circumferentially extending cam surfaces wherewith said projections engage.

2. A telescoping flue comprising at least two sections, one of which fits within the other with appreciable clearance when the sections are in any but fully extended condition, a locking ring fitted within one end of the outer section, the same being provided with a series of L-shaped slots, the inner section having a circumferential portion adjacent its opposite end of increased external diameter and of a size to fit rather closely said locking ring, projections on said portion that are arranged to occupy the aforesaid slots when the flue is in extended condition, the outer and

inner sections being surrounded in the vicinity of said portions, respectively, by inwardly and outwardly extending seats that engage each other and substantially seal the joint between the sections when said projections occupy locking positions within said slots.

3. A telescoping flue comprising at least two sections, one of which fits within the other with appreciable clearance when the sections are in any but fully extended condition, a locking ring secured within one end of the outer section, the same being provided with a series of L-shaped slots, the outer end of the locking ring having an inwardly directed flange providing a seat, the inner section having a circumferential portion adjacent its opposite end that is of increased external diameter and of a size to fit rather closely said locking ring, there being a shoulder between the body portion of said inner section and said circumferential portion providing a seat arranged for engagement with the previously mentioned seat, and projections extending from said circumferential portion that are arranged to occupy said slots when the flue is in extended condition, certain walls of said slots that are adapted to be engaged by said projections being inclined in a direction to produce relative axial movement between the sections as one section is turned with respect to the other such as will urge said seats into firm contact with each other.

4. A telescoping flue comprising relatively movable flue sections and incorporating a soot collecting basin having a discharge opening, closure means for said opening biased toward closed position, and a part connected to and movable in unison with said closure means, said part being engaged and shifted by certain of said sections during contraction of the flue thereby to move the closure means to open position.

5. A telescoping flue comprising relatively movable flue sections and incorporating a soot collecting basin having a discharge opening, a closure for said opening, means tending to retain the closure in closed position, and a part connected to and movable in unison with said closure, said part being engaged and shifted by certain of said sections during contraction of the flue thereby to move the closure to open position in opposition to said means.

6. A telescoping flue comprising a base section and one or more retractable sections, the base section having a side aperture spaced above its lower end for communicative connection with a combustion apparatus, the portion of the base section below said aperture enclosing a soot-collecting basin, the section being provided with an opening through which soot may be discharged, a closure for said opening, means tending to retain said closure in closed position, and means engaged by the retractable section or sections when the flue is contracted for shifting said closure to open position in opposition to the first mentioned means.

7. A telescoping flue comprising a base section and one or more retractable sections, the base section having a side aperture spaced above its lower end for communicative connection with a combustion apparatus, the portion of the base section below said aperture enclosing a soot-collecting basin, the section being provided with an opening through which the soot may be discharged, a closure for said opening, means tending to retain said closure in closed position, further means engaged by the retractable section or sections when the flue is contracted for shifting

said closure to open position in opposition to the first mentioned means, and a releasable instrumentality for holding the retractable section or sections in retracted position.

8. A telescoping flue comprising a base section and a retractable portion, the base section being open at its lower end and having an aperture in its side spaced above said lower end and through which the flue is adapted to have communicative connection with a combustion apparatus, a closure for the lower end of the base section, a spring tending to retain the same in closed position, the closure including a part arranged to be engaged by the lower part of the retractable portion whereby to shift the closure to open position against the tension of said spring when the flue is contracted, means carried by the top of the base section that is arranged for holding engagement with the top of a retractable portion for holding the latter in retracted position.

9. A flue comprising a base section open at its lower end, and a plurality of nesting retractable sections that telescope into the base section, the base section having an aperture in its side that is spaced a distance above its lower end whereby the portion of said base section below the plane of said aperture provides a soot-collecting basin, a closure arranged to engage the lower end of the base section, guide means thereon slidably engaging parts of the base section thereby to retain the closure in operative relation to the base section, a substantially U-shaped bail pivoted at its ends to diametrically opposite parts of the base section near the bottom thereof so that the central portion of said bail may occupy a position below the bottom of the base section, a spring compressed between the central portion of said bail and the closure, and parts on the closure arranged to be engaged by the lower ends of the retractable sections, when the flue is in retracted condition, for depressing the closure in opposition to said spring and thus opening the soot-collecting basin.

10. A flue comprising a base section that is open at its lower end and a plurality of nesting retractable sections that telescope into the base section, the base section having an aperture in its side that is so spaced above its lower end that the portion of said base section below the plane of said aperture provides a soot-collecting basin, an inverted dished closure having a peripheral flange arranged to engage the lower end of the base section, guide means rising from the closure and slidably fitting within the lower end of the base section to retain the closure in operative relation to the base section, a substantially U-shaped bail pivoted at its ends to diametrically opposite parts of the base section near the bottom thereof so that the central portion of said bail may occupy a position below the bottom of the base section, means for releasably holding the bail in said position, a spring seat with spring positioning

means carried by the central portion of said bail, a spring having its lower end engaged with said positioning means and resting upon said seat and compressed between the same and the closure, and parts on the closure arranged to be engaged by the lower ends of the retractable sections when the flue is in retracted condition for depressing the closure in opposition to said spring and thus opening the soot-collecting basin.

5 11. A telescoping flue comprising a base section that is open at the bottom, and a plurality of nesting retractable sections that are adapted to be contracted into the base section, the base section having an opening in its side spaced above its lower end through which the flue is adapted

15 to be communicatively connected with a combustion apparatus, the flue enclosing a soot-collecting basin below the plane of said opening, a closure for the bottom of the base section, a spring tending to retain the same in closed position, the

20 closure having a part engaged by the lower ends of the retractable sections when the flue is in contracted condition for opening said closure in opposition to said spring, a cap fastened to the top of the inner retractable section provided with

25 an outwardly extending flange that overhangs the other sections, a hook rising from one side of the base section and positioned for engagement with the top of said flange thereby to retain the retractable sections in retracted position, the flange being cut away at one side to permit the flange to pass said hook, and diametrically op-

30 posed lugs on the cap to facilitate turning the same so as to shift said cut-away portion of the cap out of register with said hook.

35 12. A telescoping flue comprising a base section that is open at the bottom, and a plurality of nesting retractable sections that are adapted to be contracted into the base section, the base section having an opening in its side spaced above its lower end through which the flue is adapted to be communicatively connected with a combustion apparatus, the flue enclosing a soot-collecting basin below the plane of said opening, a closure for the bottom of the base section, a spring tending to retain the same in closed position, the

40 closure having a part engaged by the lower ends of the retractable sections when the flue is in contracted condition for opening said closure in opposition to said spring, a cap fastened to the top of the inner retractable section provided with an outwardly extending flange that overhangs the other sections, a hook rising from one side of the base section and positioned for engagement with

45 the top of said flange thereby to retain the retractable sections in retracted position, the flange being cut away at one side to permit the flange to pass said hook, a socket formed in said flange

50 for the reception of said hook, a detent on one side of the socket, and a stop on the other side thereof.

55 13. A telescoping flue comprising a base section that is open at the bottom, and a plurality of nesting retractable sections that are adapted to be contracted into the base section, the base section having an opening in its side spaced above its lower end through which the flue is adapted to be communicatively connected with a combustion apparatus, the flue enclosing a soot-collecting basin below the plane of said opening, a closure for the bottom of the base section, a spring tending to retain the same in closed position, the

60 closure having a part engaged by the lower ends of the retractable sections when the flue is in contracted condition for opening said closure in opposition to said spring, a cap fastened to the top of the inner retractable section provided with an outwardly extending flange that overhangs the other sections, a hook rising from one side of the base section and positioned for engagement with

65 the top of said flange thereby to retain the retractable sections in retracted position, the flange being cut away at one side to permit the flange to pass said hook, a socket formed in said flange for the reception of said hook, a detent on one side of the socket, and a stop on the other side thereof.

MARC RESEK.
